(57) **CLAIM**

The ornamental design for a eyeglass ear support arms having integrated hearing protection members, as shown and described.

DESCRIPTION

FIG. 1 is a left side view of an eyeglass ear support arms having integrated hearing protection members of the present invention;

FIG. 2 is a right side view thereof;

FIG. 3 is an enlarged top view thereof;

FIG. 4 is a front view thereof;

FIG. 5 is a an enlarged bottom view thereof; and,

FIG. 6 is a left perspective view thereof.

The broken lines immediately adjacent shaded areas in FIGS. 3 and 4 represent bounds of the claimed design while the broken line shown parts of the eyeglass are directed to environment and are for illustrative purposes only. The broken lines form no part of the claimed design.
